B. MILLS ET AL

HEATING SYSTEM

Filed Jan. 24, 1921

UNITED STATES PATENT OFFICE.

BERNARD MILLS, OF BROOKLYN, NEW YORK, AND REUBEN R. ROW AND HOWARD C. DAVIS, OF ELIZABETH, NEW JERSEY, ASSIGNEES TO ROW & DAVIS, ENGINEERS, INC., A CORPORATION OF DELAWARE.

HEATING SYSTEM.

Application filed January 24, 1921. Serial No. 439,644.

To all whom it may concern:

Be it known that we, BERNARD MILLS, REUBEN R. Row, and HOWARD C. DAVIS, citizens of the United States, the former residing at Brooklyn, in the county of Kings and State of New York, and the two latter residing at Elizabeth, in the county of Union and State of New Jersey, have invented certain new and useful Improvements in Heating Systems, of which the following is a full, clear, and exact description.

This invention relates to the heating of congealed or thickened liquids to render them liquid or mobile and to maintain them in that condition. Many substances, such as, for example, heavy petroleum oils, asphalt, molasses, etc., congeal or thicken into a solid or gelatinous mass below certain temperatures and when in that condition their removal and transfer presents many difficulties. While the application of sufficient heat will render them mobile and easily handled by pipes, difficulty has heretofore been experienced in applying the heat successfully. A common method heretofore employed for applying the heat has been by means of steam coils located within the storage tanks. With this method the mass immediately surrounding the coils will be rendered mobile or liquid, but as no successful circulating means has been provided the remainder of the mass will be substantially unaffected. If there is a leak in the coils the substance being handled is diluted and the water so added must be subsequently removed. In order to make repairs or to establish the existence of a leak, the tank must first be emptied. The steam coils also occupy considerable space and decrease the capacity of the tanks. In marine installations, the space between the inner and outer bottom skins of a ship is commonly utilized for tanks for the storage of the heavy fuel oil and because of the proximity of the tanks to the cold sea water, the oil quickly congeals or solidifies. These tanks are very inaccessible because of their location in the extreme bottom of the ship, and owing to the large amount of bracing in these tanks the installation of steam coils therein is very slow, difficult, and expensive, and the coils are almost inaccessible for inspection and repair.

An object of our invention is to provide a

heating system for such purposes which will largely eliminate the above mentioned defects and difficulties. More particularly our object is to provide a system in which the piping necessary within a tank is very small with a consequent elimination of danger of leaky joints, in which the piping is practically all exposed and readily accessible for inspection and repair, and in which the capacity of the tanks is not materially decreased. A further object is to provide a system which is comparatively inexpensive and simple in construction, installation and operation, which is reliable, rapid and efficient, which permits of a positive control of the temperature of the contents of a storage tank, and in which repairs can be effected without first removing the contents of any of the tanks. Other objects and advantages will be apparent from the following description and the novel features of our invention will be particularly pointed out in claims.

The invention contemplates the preliminary heating of a quantity of a liquid, preferably of the same substance as that in the storage tank, transferring this liquid preferably as a shifting jet into direct contact with the thickened, congealed, or jellied substance to break up and dissolve or liquefy a portion of the same and absorb it into the treating liquid, removing the mixture, heating it, and reapplying it to stored substance, repeatedly until the entire content of a tank is made liquid and mobile and raised to a desired temperature. A portion of the circulating mixture can be diverted to another or intermediate tank, or utilized in any desired manner at the same time that the contents of a tank are being liquefied or maintained in a liquid condition. The pipe carrying the heated liquid to the tanks may be disposed within or surrounding the suction pipe through which the liquid is removed from the tank, so that the suction removal pipe will be heated and its contents kept mobile. The invention also comprises certain details and arrangements which will be more fully hereinafter described.

In the accompanying drawing:

Fig. 1 is a schematic view of an apparatus arranged in accordance with our invention for use in marine installations;

Fig. 2 is a plan of a tourniquet device or

reaction turbine for setting up the shifting jet; and

Fig. 3 is a sectional elevation of the same, taken substantially along the line 3—3 of Fig. 2.

Referring now to the drawings, we may utilize the usual deep or small tank 1 as an element of our system. A pump 2 is connected at its intake side to the lower part of the tank 1 by means of a pipe 3 having therein a controlling valve 4. The pump is connected at its discharge end by a pipe 5 with one end of a heating coil 6 of a central heater 7. The other end of the coil 6 is connected to a pipe 9, and a branch 10 of this pipe having a valve 11 therein leads to the upper portion of the deep or settling tank 1. A branch of the pipe 9 has a valve 12 therein and the portion 13 beyond the valve extends into a storage tank 14 and to a point therein adjacent the suction outlet 15 of the tank. The suction outlet is connected by a pipe 16 with the intake side of the pump 2 and the pipe 16 has a valve 17 therein. Steam from any suitable source is supplied to the heater 7 by means of a pipe 18 having a controlling valve 19 therein, and the condensation is removed by a pipe 20 having a controlling valve 21 therein. The pipe 9 may and preferably does have one or more branch pipes 22 leading therefrom to distant parts of the storage tank 14, and each branch 22 is controlled by a valve 23 therein.

The end of the pipe 22 enters the tank and carries a collar 24 threaded thereon and fixed against unscrewing by a headless set screw 25. A hydraulic tourniquet device or reaction turbine is carried by the end of the pipe 22 and collar 24 so as to produce a shifting jet of any liquid passing therethrough. This device may conveniently comprise a nozzle 26 having an annular inner seat 27 at its larger end which fits over the end of the pipe and its collar and has rotary bearing thereon. A ring 28 which fits loosely on the pipe above the collar, with an inner diameter less than the outer diameter of the collar, is also received within the seat 27 abutting the collar and secured to the nozzle by means of a plurality of set screws 29 which pass through the nozzle into the ring. The nozzle is free to rotate on the collar secured to the pipe and is restricted against movement longitudinally of the pipe by the engagement of a shoulder 30 and the ring 28 of the nozzle with the opposite ends of the collar. The nozzle has a bore approximately equal to that of the pipe 22 at the end connected to the latter, and the bore tapers gradually to a smaller orifice at the free end. The nozzle curves downwardly and arcuately in a horizontal direction at the same time, so that the axis of the orifice is at one side of and lateral to the axis of rotation of the nozzle. The passage of a jet of liquid through the hori-

zontally curved nozzle imparts to the latter a rotary movement, the rate of rotation being proportional to the velocity of the jet.

In use, when starting the valves 17, 21, 23 and 12 will be closed and the valves 4, 11 and 19 will be opened. The opening of valve 19 admits steam to the heater and the oil within the coil 6 is heated. The pump will be started and will force the hot oil through pipes 9 and 10 into the deep or small tank and from the latter will be carried back through pipe 3 to the pump and thence through pipe 5 to the coil 6. The oil is thus caused to circulate repeatedly through the heater and the deep or small tank with the result that the oil in the deep tank becomes heated to any desired temperature. When the oil in the deep or small tank is hot enough the valve 12 will be opened slightly and the valve 17 entirely opened. A portion of the oil from the heater 7 will now pass through the pipes 9 and 13 into the storage tank and this heated oil will melt or liquefy a portion of the jellied or solidified oil by its direct contact therewith around the suction outlet opening 15. This oil will be drawn through the opening 15 and pipe 16 to the pump and then be passed through the heater 7 to have its temperature raised. This oil is again pumped into the storage tank by pipes 9 and 13, the valve 12 being operated to increase the flow therethrough as the operation proceeds so as to increase the quantity and velocity of the moving column through the pipe 9, and the valves 11 and 4 partially closed. The oil circulation will then be mainly between the pump, heater and storage tank and increasing amounts of the congealed oil in the storage tank will be liquefied. The action of the moving jet of hot oil upon the congealed mass tends to break the latter up and assist in its liquefaction due to the presentation of the greater surface of the small particles of congealed oil to the action of the incoming hot oil. The small amount of the oil diverted through the deep tank will keep the contents thereof hot and mobile and will maintain this tank, from which the working supply is drawn, filled continuously. The valve 23 may be opened and some of the heated oil discharged by means of pipe 22 and nozzle 26 into the tank 14 at points distant from the outlet 15 to liquefy the remainder of the oil in the tank. Increasing amounts can be admitted through pipe 22 by operating valves 12 and 23 so that the entire contents of the storage tank 14 can soon be liquefied, raised to any desired temperature, and maintained in that condition. The nozzle gives the jet considerable velocity so that the striking of the jet upon the congealed mass will disintegrate and break up the latter into small particles so as to thereby present greater surface area to the action of the hot circulating liquid, which facilitates and

hastens the heating and rendering mobile of the tank contents. As greater quantities of the circulating liquid are diverted through the nozzle the velocity of the jet will increase so that the shifting jet will strike the congealed mass at increasing distances from the pipe 22 and therefore one nozzle will cause the disintegration or breaking up of a considerable area of the tank. As many pipes 22 and nozzles will be provided as necessary for the size tank to which they are attached. The circulating liquid after contacting with the congealed mass will flow over the same to the outlet and carry with it into circulation a quantity of the mobile contents.

Whenever more than one storage tank, such as the tank 14^a, is employed, the pipe 9 will have a branch 31 leading thereto with terminal pipes 22^a and 13^a, and valves 12^a and 23^a operating the same as the corresponding parts for the tank 14. We provide as many branch pipes 22^a as necessary for each tank and each preferably has a nozzle 26^a similar to the nozzle 26 on the outlet end of pipe 22. The outlet or suction pipe 16^a from the tank 14^a corresponds to the pipe 16 and is controlled by a valve 17^a corresponding to the valve 17. Both pipes 16 and 16^a are connected to the intake side of the pump 2. The tanks 14 and 14^a can therefore be heated simultaneously or separately as desired by suitable regulation of the controlling valves. The valve 21 and pipe 20 leading from the heater 7 permit the removal of the condensed steam at suitable intervals. The working supply of oil is withdrawn as needed from the deep tank 1 by means of an outlet 32.

When the oil in the deep tank is hot, and a supply in a new tank is to be used, it is only necessary to operate the pump and operate the valves leading to the new tank to cause the hot oil to pass through it as hereinbefore explained. In the application of our system to the unloading of tank cars, the deep tank 1 is replaced by a small tank having a similar function in the system.

It will thus be seen that in the practice of this invention, practically no piping in the interior of the storage tanks is necessary, and the other piping is exposed so as to be readily accessible for inspection and repairs. In case of leakage no water can escape into the tanks and dilute the oil or other liquid and so necessitate its separation from the liquid or oil before use. The amount of piping necessary is small and can be easily, rapidly and inexpensively installed. The elimination of the steam coils from the tanks increases the capacity of the tanks and when repairs are necessary they can be made without the necessity of emptying any of the tanks. The space occupied by the apparatus is small and one heating unit does the work

for all storage tanks which not only simplifies the system but cuts down the installation cost materially. The system is readily adaptable to present constructions of ships, without material changes or alterations in their construction. In cold weather, the speed of the pump can be increased to increase the rate of heat transfer, and the quantity of steam admitted to the heater can also be increased in order to increase the rate of heat transfer, and the quantity of steam admitted to the heater can also be increased in order to increase the temperature. The system is therefore adaptable to all operating conditions and is positive, efficient, 80 and reliable in operation.

While we have illustrated and described our system in connection with the handling of heavy fuel oils, it is to be understood that such illustration is for the purpose of explanation only, and that the invention is capable of application to the handling of other substances having similar congealing or thickening properties.

By the use of the word "oil" in the claims we mean those oils which congeal or form a viscous jelly at the lower temperatures that are commonly encountered, and also other materials having similar congealing and thickening properties.

While any liquid may be used in the small tank and heater for starting purposes, the use of a liquid similar to or the same as the substance to be handled is preferable.

It will also be understood that various changes in the details and arrangements herein described and illustrated may be made by those skilled in the art within the principle and scope of our invention.

We claim:

1. In a heating device, the combination of a heater, means forcibly circulating a mobile liquid through the heater repeatedly, a storage tank for congealed liquids, a pipe opening into the tank and having on its outlet a hydraulic tourniquet device, and means for diverting variable portions of the circulating liquid through the said tourniquet device so as to provide a shifting jet having a considerable velocity to impinge upon the congealed contents of the storage tank and break up, disintegrate, and render mobile a portion of the contents and carry it into the circulating liquid.

2. A heating device comprising a storage tank, a pumping device, connections between the pumping device and said tank for circulating a liquid through the latter, the inlet and outlet ends of the connections in the tank being disposed adjacent to each other, a branch connection between the inlet connection and a distant portion of the tank having at its terminal within the tank a hydraulic tourniquet device for automatically producing a shifting jet of liquid issuing

ing therefrom to impinge upon the congealed contents of the tank and break up and render mobile the same, and carry it into the circulating liquid, and means for heating the circulating liquid.

3. A heating device comprising a storage tank, a pumping device, connections between the pumping device and the tank for circulating a liquid through the latter, the 10 inlet connection to the tank having at its orifice within the tank a hydraulic tourniquet device for automatically producing a shifting jet of the incoming liquid to impinge upon the congealed contents of the 15 tank and break up and render mobile the same and carry it into the circulating liquid and means for heating the circulating liquid.

4. A heating device comprising a small tank, a pump, a heater, pipes connecting 20 the tank, pump and heater in series whereby a heated liquid can be circulated through the tank by the operation of the pump, a storage tank, inlet and outlet pipes connecting said storage tank with the pipes leading 25 to said small tank, the terminals of said inlet and outlet pipes within the storage tank being disposed adjacent one another, a branch inlet pipe connected to said inlet pipe and leading to a distant portion of the 30 storage tank, a hydraulic tourniquet device

within the tank and connected to the end of the branch inlet pipe, a valve in each of said pipes whereby any desired portion of the heated liquid can be diverted through the storage tank by means of either or both of 35 the inlet pipes.

5. In a heating device, the combination of a storage tank, inlet and outlet pipes leading to said storage tank with their terminals within the tank disposed adjacent 40 each other, a branch inlet pipe leading from said inlet pipe to a portion of the tank distant from the other inlet terminal, a hydraulic tourniquet device disposed within the tank and connected to the branch inlet 45 pipe, and means for circulating a heated liquid through said storage tank by means of said inlet and outlet pipes.

6. The method of changing oil from the congealed to the mobile state, which comprises repeatedly subjecting the congealed oil to direct contact with a shifting jet of heated oil, to render mobile the desired amount of the congealed oil.

In testimony whereof we hereunto subscribe our signatures.

BERNARD MILLS.
